UNITED STATES PATENT OFFICE.

CLAUD A. SEARS, OF COLUMBUS, GEORGIA, ASSIGNOR TO CHERO-COLA COMPANY, OF COLUMBUS, GEORGIA, A CORPORATION OF GEORGIA.

DESIGN FOR A BOTTLE.

Application filed August 25, 1923. Serial No. 7,086. Term of patent 3½ years.

To all whom it may concern:

Be it known that I, CLAUD A. SEARS, a citizen of the United States, residing at Columbus, in the county of Muscogee and State of Georgia, have invented a new, original, and ornamental Design for Bottles, of which the following is a specification, reference being had to the accompanying drawing, forming a part thereof.

I claim:

The ornamental design for a bottle, as shown.

CLAUD A. SEARS.
